[57] **CLAIM**

We claim the ornamental design for portable focused beam searchlight, as shown and described.

DESCRIPTION

FIG. 1 is a perspective view of the searchlight.

FIG. 2 is a bottom elevational view of the searchlight with the finned heat sink and lens on the left end of the searchlight, showing the tripod mount in plan view.

FIG. 3 is a side elevational view of the searchlight with the finned heat sink and lens being on the left end of the searchlight, showing the pushbutton control switch and carrying handle in side elevational view. The left and right side elevational views are identical.

FIG. 4 is a top elevational view of the searchlight with the finned heat sink and lens being on the left end of the searchlight, showing the pushbutton control switch and carrying handle in top elevational view.

FIG. 5 is a front elevational view of the searchlight looking into the lens, reflector, and xenon arc lamp;

FIG. 6 is a rear elevational view of the searchlight showing an external electrical connector; and,

FIG. 7 is a rear elevational view thereof.
